UNITED STATES PATENT OFFICE.

BENJAMIN F. PEETZ, OF MORO, OREGON.

COPY-HOLDER.

957,798.

Specification of Letters Patent. Patented May 10, 1910.

Application filed December 3, 1908. Serial No. 465,780.

To all whom it may concern:

Be it known that I, BENJAMIN F. PEETZ, a citizen of the United States, and a resident of Moro, in the county of Sherman and State of Oregon, have made certain new and useful Improvements in Copy-Holders, of which the following is a specification.

My invention relates to copy holder attachments for typewriters and consists in 10 the constructions, combinations and arrangements of parts hereinafter described and claimed.

The main object of my invention is to provide a copy holder which will bring the lines 15 of the copy into view in front of the operator consecutively as the platen is rotated for line spacing.

A further object of my invention is to provide means for operating the copy holder 20 so that it will feed the copy faster or slower and in such a manner as to be entirely independent of the rotation of the platen.

My invention is illustrated in the accompanying drawing, in which—

25 Figure 1 is a front view showing one embodiment of my invention, and Fig. 2 is an end view showing the means by which the copy holder roller is operated.

In Fig. 1 A is the carriage frame of a 30 typewriter such as the Underwood, Smith or Remington. B is the platen which is mounted upon a shaft 1 and is arranged for movement by means of the thumb wheel 2. Secured to the carriage A is an upright 35 frame consisting of the side pieces 3 and 3', provided with inwardly turned flanges at their lower ends 4 and 4' connected with the upright members 3 and 3' by means of the braces 8, 8'. A cross piece 5 which is 40 preferably a flat strip connects the members 3, 3', and braces 7, 7' serve to strengthen the same and to prevent side movement. The frame thus described is secured to the carriage by means of the screws 10 and 10' 45 which pass through the lower flanges 4, 4' as clearly shown in Fig. 2.

In the upper part of the frame is located a copy holder roller 12, supported on a shaft 13 journaled in the upright members 3 and 3'. On one end of the shaft 1 is located a thumb wheel 14. At the opposite end the shaft is provided with a line-spacing device which consists of the ratchet wheel 15 mounted upon the shaft 1, the shield 16, 55 pawl 17 and the line-spacing lever 18. The

shield 16 is also mounted upon the shaft and is provided with the adjusting handle 19 for shifting the shield relatively to the pawl 17.

The shield may be adjusted in one of three positions. In its first position the end of 60 the pawl 17 glides over only a short portion of the shield before engaging the teeth of the ratchet 15, when the spacing lever 18 is manipulated. As soon as the pawl engages a tooth on the wheel 15 the platen is 65 turned, in this instance a distance equal to the space between three lines. In the second adjustment of the shield 16 the latter prevents the pawl from engaging the teeth of the ratchet wheel as soon as it otherwise 70 would, and in the second position the platen is moved a distance corresponding to two lines. The third adjustment similarly gives a movement of the platen of only one line.

Referring now to Fig. 2 it will be seen 75 that one leg of the upright 3 is provided with a lug 20 to which is pivoted a bell crank lever 21. The lower end of the latter is arranged to be engaged by the inner end of the line-spacing lever 18, so that when the 80 pawl 17 is moved the lever 21 is also moved inwardly. On the other arm of the lever 21 is pivotally attached a pawl 22, which is adapted to engage the teeth of the ratchet 23 85 located upon the shaft 13. The ratchet 23 is provided with a shield 24 against which the pawl 22 is normally held by means of the spring 22'. The shield 24 is similar to the shield 16 on the ratchet 15, which serves the same purpose of varying the throw of 90 the pawl 22, thereby turning the copy holder roller different distances. The shield 24 is provided with an adjusting handle 25 similar to the handle 19 of the shield 16.

In order to provide frictional resistance 95 to the positive movement of the copy holder roller 12 I have arranged the spring member 26, which is pivoted at 27 upon the upright 3 and bears at its end a head 28 of semi-cylindrical shape and of such a size that it 100 will enter the outer openings between the teeth far enough to form an opposing element to the motion of the wheel when slight power is applied, but may be pushed out of the way by the teeth when enough power is 105 applied to the wheel in either direction. In order to give sufficient tension to the spring 26 I provide a cam member 29 which may be turned to bear against the spring at different points on the cam surface, thereby providing 110

a means for adjusting the pressure of the head 28 against the teeth of the ratchet. The arrangement thus described provides means for permitting the movement of the 5 copy holder roller in response to the positive action of the pawl 22, while preventing any extra movement of the roller or the accidental rotation thereof. At the same time, owing to the cam shape of the head 28, 10 the roller may be turned in either direction so that the paper may be quickly pulled out either from one side or the other. I desire especially to call attention to the fact that if an ordinary spring-locking dog were to 15 be used, the paper could not be pulled out from the opposite direction in which the roller can be turned without releasing the dog, and I consider this a decided advantage in my holder.

20 From the foregoing description of the various parts of the device the operation thereof may be readily understood.

As has been already explained, the invention constitutes an attachment which may be 25 applied to any standard typewriter, but as illustrated, is applied to the Underwood. In this machine the line-spacing is accomplished by moving the lever 18 to the right or to the left. This actuates the pawl 17 in 30 the manner already described and at the same time moves the lever 21. It will be observed that the throw of this lever 21 is the same at every movement of the lever 18, but that the effect of its throw may be varied 35 by means of the adjusting shield 24 on the copy holder roller so that the latter may space three lines while the platen B is spacing one line. In fact the motions of the two rollers are entirely independent of each other

although caused by a movement of the same 40 lever.

I claim—

1. In a copy holder attachment for type-writer machines, the combination with the line-spacing lever, of a frame, a roller journaled in said frame, a ratchet wheel attached to the shaft of said roller, a bell-crank lever pivoted on said frame, a spring-pressed pawl carried by said bell-crank lever and arranged to engage the teeth of said ratchet wheel, one end of said bell-crank lever being adapted to be engaged by said line-spacing lever, a friction member normally in engagement with the teeth of said ratchet wheel, and means for varying the pressure 55 of said friction member.

2. In a copy holder, attachment for type-writer machines, the combination with a line-spacing lever, of a frame, a shaft journaled in said frame, a roller on said shaft, a ratchet wheel attached to one end of the shaft of said roller, a bell-crank lever pivoted on said frame, a spring-pressed pawl pivotally mounted on one end of said bell-crank lever, and arranged to engage the 65 teeth of said ratchet wheel, the other end of said bell-crank lever being out of normal engagement with, but adapted to be engaged by the line-spacing lever, a spring friction member, normally in engagement with the 70 teeth of said ratchet wheel, and a cam secured to said frame, and arranged to engage said spring friction member for varying the pressure of the latter, upon the ratchet wheel.

BENJAMIN F. PEETZ.
